AUXILIARY LUBRICANT AND VAPOR HEATING SYSTEM FOR INTERNAL COMBUSTION ENGINES

Ray H. Masters, Huntington Park, Calif.

Application May 11, 1953, Serial No. 354,205

7 Claims. (Cl. 123—142.5)

My invention relates generally to improvements in internal combustion engines, and more particularly to an auxiliary vapor heating system for maintaining exposed covers and other wall surfaces at the engine operating temperature.

In an internal combustion engine lubrication of the crankshaft, pistons, connecting rods and bearings is, of course, essential, but it is also necessary to lubricate the valve mechanisms, camshafts, timing gears, and the like. For this reason, oil is pumped from the crankcase to various lubrication points in the engine, from whence it flows back into the crankcase. Of necessity, various working chambers within the engine are thus open to the crankcase, and the lubricating oil is subject to contamination and dilution by reason of the impurities picked up during its travel.

Among the chambers or working spaces open to the crankcase are those in which are mounted the valve cam-shaft, lifters, push rods, and valve stems. In the case of an overhead valve engine, space is also provided for the mounting of the rocker arm shaft and rocker arm assemblies. Another important chamber which is open to the crankcase is the timing gear or gear chain space. All of the aforementioned chambers are normally closed by external cover plates which have large areas exposed to the outside air, are cooled rapidly, and are normally considerably below the operating temperature of the engine block and crankcase. Consequently, they present a relatively cold wall surface in the chamber which they close.

In addition to the oil circulating through the lubrication system, volatile gases and products of combustion from the combustion chambers enter the open spaces within the engine as a result of piston blowby and valve leakage. Such gases include water vapor, raw or unburned fuel, and exhaust vapors. Outside air containing dust and other contaminating substances is also introduced into the engine. Thus, in any of the chambers in which the liquid lubricating oil is covering the moving parts, the oil is subject to intimate contact with various gases laden with substances which, if condensed into the liquid oil, form emulsions and sludge as well as destroying the lubricating qualities of the oil. In particular, the rapid condensation of the mixture of gases present in the engine causes oxidation which results in the formation of highly corrosive acid compounds. All of this impairs the efficiency of the lubricating system, causes additional friction and wear, so as to decrease the power output of the engine, and reduces its useful life.

Because volatile gas vapors and steam are harmful if allowed to remain in the engine, it is conventional to provide an engine breather tube to remove the vapor, but such a breather is only partially effective, and there are necessarily large volumes of vapors circulating through the open spaces of the engine at all times. To reduce the harmful effect of these vapors, I provide auxiliary heating means which tend to keep all of the circulating vapors at a temperature approaching the operating tem-

2

perature of the engine. Thus, the volatile impurities in the gas vapor will not condense into the crankcase to harm the lubricating oil and form the excessive sludge deposits which are a great source of trouble in present day engines.

In applying this principle to a preferred embodiment of the invention, I have selected the exposed cover plates as highly desirable points at which to apply auxiliary heat. Instead of presenting cold wall surfaces which tend to condense the gas vapors within the valve chambers, and the like, the covers become heat transfer surfaces which heat any cold gas vapors, and maintain all of the gases at such a temperature that condensation is reduced to a minimum. The source of heat may be any form of auxiliary heat supplied by the engine. For example, the relatively hot engine cooling liquid may be used, or heat may be extracted from the exhaust gases. The use of these increases the thermal efficiency of the engine as well as maintaining the gas vapors at an elevated temperature.

As can be appreciated, the invention may be utilized on any type of internal combustion engine both from a standpoint of the form of fuel used, and the design and construction of the engine. Likewise, the selection of points at which to apply heat is variable and it may be done on any or all exposed cover plates which are normally cold surfaces.

With the foregoing in mind, it is a major object of my invention to provide heating means for an internal combustion engine which maintains the gas vapors within the engine open spaces at an elevated temperature.

Another object of my invention is to provide vapor heating means which utilize an auxiliary source of heat from the engine, and thereby increase the thermal efficiency of the engine.

An additional object of the invention is to reduce the formation of corrosive acid compounds in the engine by preventing rapid condensation of the gaseous mixtures present in the engine.

It is also an object of the invention to provide heating means to heat the exposed cold spots of the engine such as the various exposed covers which close auxiliary engine chambers opening into the crankcase.

A further object of the invention is to provide vapor heating means which can be economically installed on existing engines and easily removed for servicing the engine.

Still another object of my invention is to provide heating means of the character described, which direct the flow of heating fluid through extended passageways in contact with the heat transfer surface to provide maximum heat transfer thereto.

A still further object of my invention is to provide vapor heating means which are simply and durably constructed for trouble-free service.

These and other objects and advantages of my invention will become apparent from the following detailed description of a preferred embodiment thereof, and from an inspection of the accompanying drawings in which:

Fig. 1 is a perspective view of an engine having my vapor heating equipment installed thereon;

Fig. 2 is a longitudinal section taken through the upper rocker arm cover and heater;

Fig. 3 is a cross-section taken along the line 3—3 of Fig. 2;

Fig. 4 is a section taken along the line 4—4 of Fig. 2;

Fig. 5 is an elevation of the side valve cover and heater;

Fig. 6 is a cross-section taken along the line 6—6 of Fig. 5; and

Fig. 7 is a front elevation of the timing gear cover and heater.

In describing my invention I have chosen to illustrate

it in connection with a gasoline engine of the overhead valve type. This type of engine is particularly susceptible to the formation of sludge and contamination of the lubricating oil because it has a large upper chamber closed by a thin-walled cover in which the oil lubricating the rocker arm assemblies is subject to contact with condensing gas vapors. It is to be understood, however, that the same principles are applicable to other gasoline engine designs and to diesel engines as well.

Referring now to the drawings and particularly to Fig. 1 thereof, the numeral 10 designates a typical engine block having a lower crankcase or oil sump 11. On the front of block 10 is mounted a belt driven fan and generator assembly 12, as well as a water pump 14 and radiator inlet hose 15. Since the illustrative engine is of the overhead valve type, it has an upper rocker arm assembly which is externally closed by an elongated rectangular cover 16 which seats downwardly against block 10 and defines an internal space 17 to receive the rocker arm assembly. Lubricating oil from the crankcase is pumped upwardly to lubricate the rocker arm shafts and bearings within space 17, and then flows downwardly through block 10 back into crankcase 11. This necessitates passages or openings between space 17 and crankcase 11.

Within space 17 is a mixture of hot gaseous vapors, which includes water vapor, raw and unburned gasoline vapors, dust from outside air and other contaminating substances. So long as these vapors do not condense they are subject to removal by the engine breather without harm to the lubricating oil. However, if the gaseous vapors condense, sludge and emulsions form, and the lighter oil fractions dilute the lubricating oil. Such harmful condensation will take place when the gaseous vapors are in contact with a cold wall surface.

In order to prevent the condensation of vapors within space 17, I form cover 16 integral with heating means so that the interior wall surface of the cover instead of being cold, acts as a heat transfer surface. For a heating medium, I prefer to use the hot water circulating through the engine cooling system. This fluid is maintained at an operating temperature of 140° to 160° F. and is therefore considerably hotter than the ambient air. Other sources of heat from the engine may also be used such as the hot exhaust gases, which are especially desirable to use on heavier fuel engines.

Hot water is withdrawn from block 10 through a rear fitting 20 connected to a T fitting 21 having one leg connected to a cover intake hose 22. The interior construction of cover 16 is best seen in Figs. 2 to 4. Cover 16 is formed of double wall construction having an outer wall or shell 23 spaced outwardly from a similar inner wall or shell 24. The shells 23 and 24 are sealed together at the bottom by a bottom flange 25 which extends outwardly and is adapted to fit tightly against the top of block 10. Both shells are easily formed of stamped sheet metal construction.

In the rear top portion of outer shell 23 is an intake fitting 27 connected to hose 22, while a similar outlet fitting 28 is mounted in the front bottom portion of the shell. Outlet fitting 28 is in turn connected to radiator inlet hose 15 by a short connecting hose 29. Between the walls of shells 23 and 24, are a plurality of horizontal elongated baffles 32 which are open at alternate ends so as to provide a single tortuous passageway or flow path between inlet and outlet fittings 27 and 28. The direction of flow is indicated by the arrows in Fig. 2. As can thus be seen, substantially the entire area of inner shell 24 forms a heat transfer surface in contact with the gas vapors within space 17. To complete cover 16, sleeves 33 are extended between shells 23 and 24 in fluidtight sealing engagement therewith, and in a position to receive conventional installation bolts 34 for holding the cover in place. The oil intake port is similarly defined by a sleeve 35 extended between shells 23 and 24, and adapted to receive a breather plug 36.

By reason of this construction cover 16 serves both as a heater and a closure for space 17. The constant flow of heating fluid through the cover serves to maintain shell 24 at an elevated temperature and prevents the gases therein from condensing. Since the heat used is auxiliary heat from the engine the thermal efficiency thereof is increased, while at the same time the formation of sludge and contamination of the lubricating oil is reduced.

The same principle is also advantageously employed at other spaces which are closed by an external cover plate. One of these is the space on the side of the engine block wherein is mounted the valve camshaft and valve lifters. This space is closed by a side cover 40 which is formed as a double-walled heater as seen specifically in Figs. 5 and 6. Cover 40 has a flat inner wall 41 and an outer wall 42 spaced outwardly therefrom by edge flanges 43 which are joined tightly to the inner wall. At the upper rear end of outer wall 42 is an inlet fitting 44, while at the bottom front end is an outlet fitting 45. Inlet fitting 44 is connected to one leg of T fitting 21 by a hose 47 and a hose 48 connects outlet fitting 45 to the radiator return hose 15.

Within walls 41 and 42 are spaced transversely extending baffles 49 which are open at alternate ends to define a tortuous flow path between fittings 44 and 45. The direction of fluid flow is shown by the arrows in Fig. 5. Thus, inner wall 41 becomes a heat transfer surface for maintaining gas vapors within the space closed by cover 40 at an elevated temperature. Since an engine breather pipe is often connected to the side cover plate, cover 40 may carry a fitting 50 extending through both walls 41 and 42, and adapted for connection to a breather pipe 51. Also, sleeves 52 may be provided for sealing off openings adapted to take installation bolts 53. As can be understood, the advantages of this construction are the same as those previously described and need not be repeated.

As a further illustrative example, I provide a timing gear cover 56 for sealing the timing gear chamber at the front of block 10. The timing gear or timing chain space is again necessarily open into crankcase and receives a supply of lubricating oil as well as gas vapors which are circulating through the open spaces within engine block 10. Cover 56 is formed of double wall construction having an outer wall formed with intake and outlet fittings 57 and 58, respectively, as seen in Fig. 7. Outlet fitting 58 is connected to hose 48 by a short coupling 60, and inlet fitting is adapted to be connected to engine block 10 by a pipe 61 (Fig. 1). Since cover 56 is of relatively small area, it is not essential to provide internal baffling means and the fluid is merely confined between the inner and outer walls while traveling between inlet fitting 57 and outlet fitting 58. As can be appreciated since the water from block 10 is at an elevated temperature, the inner wall of the cover acts as a heat transfer surface for maintaining the gas vapors in the timing gear chamber at a temperature above the condensation point.

While I have thus shown and described particular embodiments of my invention in some detail it is to be understood that changes of design and construction can be made without departing from the scope of the invention. Therefore, I do not wish to be restricted except as defined in the appended claims.

I claim:

- An auxiliary vapor heater and rocker arm assembly cover for a liquid cooled internal combustion engine comprising: an elongated inner shell shaped to fit over said rocker arm assembly and in sealing engagement with the engine block; an elongated outer shell spaced from said inner shell and sealed thereto by edge flanges to define a closed fluid passageway; means including intake and discharge fittings mounted at the end of said outer shell and adapted for connection to the return side of the engine cooling liquid system; and baffle extending be-

tween said inner and outer shells to define a tortuous path between said inlet and outlet fittings.

2. An auxiliary vapor heater and side valve cover for a liquid cooled internal combustion engine comprising: an elongated inner flat wall shaped to fit in sealing engagement with the opening in the side of the engine block; an elongated flat outer wall spaced from said inner wall and sealed thereto by edge flanges to define a closed fluid passageway; means including intake and discharge fittings mounted at the ends of said outer wall and adapted for connection to the return side of the engine cooling liquid system; and baffles extending between said inner and outer walls to define a tortuous path between said inlet and outlet fittings.

3. An auxiliary vapor heater and timing gear cover for a liquid cooled internal combustion engine comprising: an inner wall shaped to fit in sealing engagement with the engine block to close the timing gear chamber; an elongated inner flat wall spaced from said inner wall and sealed thereto by edge flanges to define a closed fluid passageway; and means including intake and discharge fittings mounted at the ends of said outer wall and adapted for connection to the return side of the engine cooling liquid system.

4. In a piston and cylinder type internal combustion engine having a crankcase, containing a reservoir lubricant; and another compartment, distinct from the cylinder and crankcase, through which the lubricant from the engine crankcase is circulated and which has removable cover means for access and is principally vapor-filled while the engine is operating; anti-condensation means for said compartment comprising: heat transfer surfaces on said cover means; and heating means associated with said heat transfer surfaces and adapted to be connected for operation by a source of heat from said engine.

5. A liquid-cooled piston and cylinder type internal combustion engine having a crankcase, containing a reservoir of lubricant; and another compartment, distinct from the cylinder and crankcase, through which the lubricant from the engine crankcase is circulated and which has removable cover means for access and is principally vapor-filled while the engine is operating; anti-condensa-

tion means for said compartment comprising: a heat transfer surface on said cover means; liquid heating means mounted on said cover means; and means for connecting said heating means to the return side of the engine cooling liquid system.

6. A liquid-cooled piston and cylinder type internal combustion engine having a crankcase, containing a reservoir of lubricant; and another compartment, distinct from the cylinder and crankcase, through which the lubricant from the engine crankcase is circulated and which has a removable cover for access and is principally vapor-filled while the engine is operating; anti-condensation means for said compartment comprising: a cover having inner and outer walls joined together to define a fluid passageway; and means for connecting said cover to the return side of the engine cooling liquid system.

7. A liquid-cooled piston and cylinder type internal combustion engine having a crankcase, containing a reservoir of lubricant; and another compartment, distinct from the cylinder and crankcase, through which the lubricant from the engine crankcase is circulated and which has a removable cover for access and is principally vapor-filled while the engine is in operation; anti-condensation means for said compartment comprising: a cover having inner and outer walls joined together to define a fluid passageway; means including intake and discharge fittings mounted on said cover for connecting said cover to the return side of the engine cooling system; and baffle means between said inner and outer cover walls to define a tortuous fluid path between said intake and discharge fittings, and in heat transfer contact with a substantial area of said inner wall.
